JACKET

Marie Tait, Bloomingdale, N. J.

Application July 7, 1953, Serial No. 25,831

Term of patent 3½ years

(Cl. D3—4)

To all whom it may concern:

Be it known, that I, Marie Tait, a citizen of the United States, residing in Bloomingdale, in the county of Bergen and State of New Jersey, have invented a new, original, and ornamental Design for a Jacket, of which the following is a specification, reference being had to the accompanying drawing, forming part thereof.

Fig. 1 is a front perspective view of a jacket showing my new design.

Fig. 2 is the rear view thereof, and

Fig. 3 is a fragmentary side view portion of the jacket shown in Figs. 1 and 2.

I claim:

The ornamental design for a jacket, substantially as shown.

MARIE TAFT
